UNITED STATES PATENT OFFICE.

JOSEPH RIMMER, OF MALDEN, MASSACHUSETTS, ASSIGNOR TO G. W. BENT CO., OF BOSTON, MASSACHUSETTS, A CORPORATION OF MAINE.

CRIB.

1,317,177.

Specification of Letters Patent. Patented Sept. 30, 1919.

Application filed July 17, 1919. Serial No. 311,622.

To all whom it may concern:

Be it known that I, JOSEPH RIMMER, a citizen of the United States, residing in Malden, in the county of Middlesex and State of Massachusetts, have invented an Improvement in Cribs, of which the following description, in connection with the accompanying drawings, is a specification, like characters on the drawings representing like parts.

10 This invention relates to cribs for children and is an improvement upon cribs of that character which have a mattress-supporting frame pivoted to be turned from a horizontal into a vertical position between head and foot frames having movable members 15 capable of being folded toward each other and substantially parallel with the mattress-supporting frame in its vertical position.

20 The present invention has for its object to provide a crib of the character described in which the movable members of the head and foot frames are connected to the mattress-supporting frame so as to be moved 25 away from each other when the mattress-supporting frame is turned into its vertical position and to be moved toward each other when the mattress-supporting frame is turned down into its substantially horizontal 30 position, for purposes as will be described.

The particular features of the invention will be pointed out in the claims at the end of this specification.

35 Figure 1 is a side elevation of a metallic crib embodying this invention.

Figs. 2 and 3, details to be referred to, Fig. 2 being a section on the line 2—2, Fig. 1.

40 Fig. 4, a plan of the crib shown in Fig. 1 in its operative position, and

Fig. 5, a plan of a portion of the crib with the mattress-supporting frame in its inoperative position.

The invention is herein shown as embodied 45 in a metallic crib, whose general construction is substantially the same as that shown in United States Patent No. 1,293,001 dated February 4, 1919, and which comprises head and foot frames *a*, *b*; side frames *c*, *d*, and

a mattress-supporting frame *e*, the head and 50 foot frames being composed of stationary members 10, to which movable members 12 are hinged or pivoted so as to be folded toward each other and into a position substantially parallel with the side member *c*, which 55 connects the stationary members 10 of the head and foot frames.

The mattress-supporting member *e* is pivoted to the stationary members 10 so as to be folded up into a substantially vertical position 60 when not in use, and the side member *d* is pivoted to the mattress-supporting member *e* so as to be folded parallel therewith when not in use.

The mattress-supporting frame *e* in its 65 lowered or operative position is supported near its front side by means of brackets 14 attached to the movable members 12 of the head and foot frames (see Fig. 1).

In the metallic crib shown and described 70 in the patent, the movable members 12 of the head and foot frames are moved outwardly by hand so as to allow the mattress-supporting frame to be turned into its upright position, and as metallic cribs of this 75 character are usually painted or enameled, it frequently happens that the person manipulating the crib fails to properly position the movable members of the head and foot frames with relation to the mattress-supporting frame, and as a result the paint or enamel on the movable members of the head and foot frames is soon scraped off on the inner side of the said movable members, 80 which renders the crib unsightly. This marring of the crib by the scraping action of the mattress-supporting frame takes place on both movements of the latter, that is, when said frame is raised and lowered. So also, 85 there is liability of the mattress-supporting frame dropping down onto and injuring the foot of the operator when said frame is lowered and the movable members of the head and foot frames are not properly positioned by the operator.

The present invention has for its object to improve cribs of the character described, so that marring of the crib and accidents to the

operator are avoided, and to this end, the movable members 12 of the head and foot frames are connected with the mattress-supporting frame, so that movement of the 5 movable members is governed or controlled by the mattress-supporting frame, and said movable members are automatically positioned properly by the mattress-supporting frame.

- 10 In the present instance, this result is obtained by two sets of levers, one set comprising the levers 16, 17, being pivoted together and having their opposite ends connected with the movable member 12 of the 15 head frame *a* and with the rear side of the mattress-supporting frame, and the other set comprising the levers 18, 19, which are pivoted together and have their opposite ends connected with the movable member 12 20 of the foot frame *b*, and with the mattress-supporting frame.

In the present instance, the levers 16, 18, are shown as pivoted to lugs 20, 21, on the 25 movable members 12, and the levers 17, 19, are pivotally connected with the mattress frame and as herein shown are pivoted at 22 with one member 23 of a hinge, whose other member 24 is pivoted at 25 with the rear side 26 of the mattress-supporting 30 frame (see Figs. 2 and 3).

In Fig. 2 is illustrated the relation of the hinge 23, 24, to the mattress-supporting frame in its horizontal or operative position, and in Fig. 3, the relation of said parts 35 when said frame is in its vertical position.

The levers and their connections with the movable members of the head and foot frames and with the mattress-supporting frame are such, that when the mattress-supporting 40 frame is turned from its horizontal or operative position into its vertical or inoperative position, the movable members have their free ends swung from each other and thereby away from the path of movement 45 of the mattress-supporting frame, as represented in Fig. 5, and as a result, the movable members 12 are prevented from being scraped or otherwise injured by the mattress-supporting frame as the latter is turned 50 up into its vertical position. On the reverse movement of the mattress-supporting frame, the movable members are swung back from the position shown in Fig. 5, toward each other and into position parallel with 55 each other as represented in Fig. 1, and this movement is so timed that the supporting brackets 14 on the movable members are brought into the path of movement of the mattress-supporting frame so as to be engaged by the end bars 27 thereof at or about 60 the time the mattress-supporting frame reaches its horizontal or operative position.

The outward movement of the movable members 12 is limited as herein shown by the stationary members 10 (see Fig. 5), and the 65 inward movement of the members 12 under the influence of the mattress-supporting frame is limited by the levers 16, 17, 18, 19, which are brought into a substantially straight position as shown in Fig. 4, with 70 a lip or flange 30 on the levers 17, 19, engaging the levers 16, 18, said lips being brought into engagement with the levers 16, 18, at or about the time the members 12 have been brought into alignment with the members 10. 75

It will be understood, that after the mattress-supporting frame has been turned up into its vertical position represented in Fig. 5, the movable members 12 are capable of 80 being turned by the operator toward each other and into a position substantially parallel with the mattress-supporting frame with the latter in its vertical position, the levers 16, 18, being capable of turning on 85 their pivots 31 without hindrance by the lips 30.

One embodiment of the invention is herein shown, but it is not desired to limit the invention to the particular construction 90 shown.

Claims:

1. In a crib, in combination, head and foot frames having movable members, a mattress-supporting frame located between 95 said head and foot frames and pivoted to be turned into a substantially vertical position, means on said movable members for supporting said mattress-supporting frame in the lowered position of the latter, and levers connecting said movable members with said mattress-supporting frame to be moved outwardly when said mattress-supporting frame is turned into its vertical position and to be moved inwardly into the 100 path of movement of said mattress-supporting frame when the latter is turned down into its horizontal position.

2. In a crib, in combination, head and foot frames having movable members, a 110 mattress-supporting frame located between said head and foot frames and pivoted to be turned into a substantially vertical position, and means for connecting said movable members with the mattress-supporting frame, to cause the latter to move the 115 movable members when the mattress-supporting frame is turned from a horizontal into a vertical position and vice versa.

3. In a crib, in combination, head and foot frames having movable members, and a mattress-supporting frame located between said head and foot frames and connected with said movable members to auto- 120

matically move the latter when the mattress-supporting frame is turned from a horizontal into a vertical position and vice versa.

4. In a crib, in combination, a mattress-supporting frame pivoted to be turned from a horizontal into a substantially vertical position, and movable head and foot members

connected therewith to be moved away from each other when the mattress-supporting frame is moved into its substantially vertical position. 10

In testimony whereof, I have signed my name to this specification.

JOSEPH RIMMER.
